Inventor
Samuel M. Edwards.

By *King Harness* Attorney

UNITED STATES PATENT OFFICE.

SAMUEL M. EDWARDS, OF DETROIT, MICHIGAN.

TOOL FOR REMOVING AND REPLACING VALVE GUIDES.

Application filed February 27, 1922. Serial No. 539,746.

To all whom it may concern:

Be it known that I, SAMUEL M. EDWARDS, a citizen of the United States, residing at Detroit, county of Wayne, and State of Michigan, have invented a new and useful Improvement in a Tool for Removing and Replacing Valve Guides, of which the following is a specification, reference being had therein to the accompanying drawings.

10 Internal combustion engines are provided with a series of valves known as intake and exhaust valves, the purpose of which is to alternately open and close the passageways between the gas intake and the cylinder and 15 the exhaust passageway and the cylinder respectively. These valves are provided with guides or bearings within which they are adapted to move.

It is oftentimes desirable to remove these 20 valve guides or bearings and the removal of the same is a somewhat difficult and tedious operation owing to the fact that it is necessary to remove the cylinder block from its setting in order to take out the valve guide 25 or bearing. It is also very difficult to remove these guides or bearings without cracking or otherwise damaging the cylinder block.

It is the prime object of my invention to provide a device adapted to remove the 30 valve guides or bearings without the necessity of removing the cylinder from its setting and without the danger of otherwise damaging the cylinder block.

It is a further object of my invention to 35 provide such a device adapted to be used in replacing the valve guide or bearing in its normal position.

It is a further object of my invention to 40 provide such a device of cheap and simple construction and one which may be easily operated by a novice so that the work may be done by the ordinary individual in his own garage without the necessity of taking his automobile to a repair shop.

45 My invention consists in the arrangement, combination and construction of the various parts of my improved device as described in the specification, claimed in my claim and shown in the accompanying drawings, in 50 which,

Fig. 1 is a sectional view of a cylinder block of an internal combustion engine with certain parts broken away and showing my improved device in place.

55 Fig. 2 is a sectional view taken on line 2-2 of Fig. 1 and

Fig. 3 is a sectional view taken on line 3-3 of Fig. 1.

I have shown a conventional cylinder block 1, with the main portion thereof cut away but showing the location of the valves 2, the valve seats 3 and the valve guides 4 thereon.

In the construction of my improved device, I provide a tubular member 5 with a rod 6 extending therethrough and having on one end thereof a head 7. The head 7 has a knurled face 15, as shown in Fig. 3. The opposite end of the rod 6 is screw threaded as at 8 and the nut 9 is adapted to be screwed thereon against the washer 10 which latter member bears against the face 11 of the tubular member 5.

In the practical operation of my improved device as a valve guide puller or remover, 75 the valve 2 is removed in the ordinary way from the cylinder block 1 and the lower end 12 of the tubular member 5 is placed against the cylinder block 1 directly under and around the head 13 of the valve guide or 80 bearing 4. The rod 6 is inserted through the pocket 14 in the top of the cylinder block and the aperture 17 in the end of the tubular member 5 until the knurled side 15 of the head 7 rests against the end of the valve 85 guide 4. The washer 10 and the nut 9 are then placed over the opposite end of the rod 6 and the nut 9 is screwed inwardly, thus causing a downward pressure upon the valve guide 4 by the head 7 and forcing the valve 90 guide 4 downwardly and out of the cylinder block 1. The knurled portion 15 of the head 7 on the rod 6 prevents the rod 6 from turning when the nut 9 is screwed inwardly.

When it is desired to use my improved 95 device in replacing the valve guide 4 in the cylinder head 1, the tubular member 5 is placed in the pocket 14, the rod 6 is inserted through the valve guide 4 and, the passageway 16 and the pocket 14, until it emerges 100 through the opening 17 in the top of the tubular member 5.

The washer 10 and the nut 9 are then placed on the end thereof and screwed inwardly as when the valve guide was being 105 removed with the result that the valve will be pulled upwardly through the passageway 16 into its normal position.

For the purpose of holding my device in its operating position while the valve guide 110 is being removed or replaced, I provide a handle 18 which may be grasped with one

hand by the operator and the device thus steadied while in use.

Owing to the construction of cylinder blocks on certain types of automobiles, it is sometimes necessary that the tubular member 5 be cut away as at 20 and the portion 19 removed in order for it to be used. The sloping side of the tubular member 5 which is left by the cutting away of the portion 19 as at 20, may bear against the side of the cylinder block and thus provide a bearing surface for the device, in addition to the bottom thereof.

It is obvious that some changes may be made in the arrangement and construction of the various parts of my improved device without departing from the spirit of my invention and it is my intention to cover by

my claim such changes as may be reasonably included within the scope thereof.

20

What I claim is:

A device of the class described comprising a member adapted to bear against an engine cylinder block and to be positioned adjacent a valve guide in said block, a rod extending through said valve guide and said first mentioned member and having a head on one end thereof adapted to bear against said valve guide, a nut on the other end thereof adapted to bear against said first member, whereby inward movement of said nut on said rod will cause the displacement of said valve guide, and a handle on said first member whereby the same may be held in a desired position.

SAMUEL M. EDWARDS.
